(57) **CLAIM**

The ornamental design for a holder for holding a beverage container onto a board, as shown and described.

DESCRIPTION

FIG. 1 is a perspective view of a holder for holding a beverage container onto a board, showing a first embodiment of our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a holder for holding a beverage container onto a board, showing a second embodiment of our design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken line showing of a board and a bottle is included for the purpose of illustrating environmental structure and forms no part of the claimed design.
